PNEUMATIC CONTROL FOR BOX MACHINES

Harry K. Dickermann, Buffalo, and John W. McCarthy, Lockport, N. Y., assignors to F. N. Burt Company, Limited, Toronto, Ontario, Canada, a corporation of Ontario

Original application July 7, 1927, Serial No. 203,881. Divided and this application January 14, 1933, Serial No. 651,768. Renewed June 24, 1936

15 Claims. (Cl. 93—39)

This invention relates to improvements in a pneumatic control device and with reference to some of the important specific features thereof, it relates to such a control device for controlling the handling of blanks in the manufacture of paper boxes and the like.

It is a general object of the invention to provide an improved pneumatic control whereby the automatic handling of blanks or the like is facilitated.

Another object of the invention is to provide an improved arrangement for pneumatic control whereby the pneumatic energy is controlled in an improved and efficient manner for initiating and discontinuing at predetermined periods the pneumatic holding grip upon blanks or the like, utilized in the manufacture of boxes or other articles.

A further object is to provide in a pneumatic control, an improved valve structure and operative connections therefor, whereby the pneumatic energy is effectively controlled in a predetermined manner and for the accomplishment of desired results.

Still another object of the invention is to provide in a pneumatic control, an improved valve structure for controlling pneumatic energy to a rotary and longitudinally reciprocating conduit for the accomplishment of predetermined results, and especially for the holding and handling of blanks of sheet material utilized in the manufacture of boxes and other articles.

Other objects of the invention will be in part pointed out in the following detailed description of an illustrative but preferred embodiment of the invention, and will be in part obvious in connection therewith.

The invention accordingly comprises the features of construction, combinations of elements, and arrangement of parts, which will be exemplified in the construction hereinafter set forth and the scope of the application of which will be indicated in the claims.

For a more complete understanding and disclosure of the nature and objects of the invention, reference is had to the subjoined detailed description of the illustrative embodiment and to the accompanying drawings in which:

Fig. 1 is a fragmentary side elevation, parts being in section, of the improved pneumatic control mechanism as utilized in a machine for the manufacture of boxes of paper or similar sheet material;

Fig. 2 is an enlarged view similar to Fig. 1 showing additional features of the improved

control mechanism and showing some of the parts in different positions;

Figs. 3, 4 and 5 are sectional views showing in elevation different parts of the pneumatic control valve, and

Fig. 6 is a fragmentary elevation of the mechanism for operating the pneumatic control valve.

The invention of this application is disclosed in applicants' prior co-pending application for "Box machine", Serial No. 203,881, filed July 7, 1927. This application is, therefore, a division of the prior application.

The improved pneumatic control system is herein disclosed in connection with a machine for making boxes or box parts from sheet material such as paper, or from paper blanks which are carried by a die-head in the formative operations of the box. In this form of machine, the formative operations are successively performed upon the blank at a plurality of operative stages being carried by the die-head and held in position thereon by pneumatic means controlled in a definite manner to establish the blank holding pneumatic or vacuum grip and to release it in a predetermined manner.

As herein disclosed, the die-head 10 is shaped to receive the box blank T and is supported by a rotary and longitudinally reciprocating spindle 11 rotatably mounted in suitable bearings in the supporting frame 13, one of these bearings being shown at 12. The bearings and connections thereto of the spindle 11 are designed not only to provide for rotation of the spindle on its longitudinal axis, but also to permit reciprocation of the spindle longitudinally of its axis.

As shown in the drawings, the die-head 10 may be in the form of a metallic block shaped in accordance with the box part to be made and cooperates with a breakdown frame 14 for shaping the blank and pressing it in contact with the surface of the die-head. Pneumatic conduits 15 are formed in the die-head opening into the peripheral faces thereof to provide pneumatic gripper ports in said faces. These pneumatic conduits communicate with an inner conduit 16 provided within the spindle 11 and extending longitudinally thereof into communication with a source of pneumatic energy such as a vacuum pump or reservoir through the flexible hose connection 17.

Any desired means may be provided (not shown) for effecting rotation of the supporting spindle 11 as required in the formative operations of the blank. Also, means are provided for effecting longitudinal reciprocation of the spindle.

For the latter purpose a rotary shaft 18 driven in any desired manner drives a rotary drum cam 19 provided with a peripheral cam slot 20 in which runs a cam lug or roller 21 carried by a sleeve 22 rotatably secured to the spindle 11. A guiding roller 23 is also carried by the sleeve 22 running in a longitudinal slot of a guideway 24 for guiding and supporting the spindle 11 in its longitudinal movements. The die-head together with its supporting spindle will be longitudinally reciprocated by rotation of the cam 19.

A pneumatic control system is provided to connect the spindle conduit 16 with a source of pneumatic energy whereby the gripper ports and the die-head are automatically energized or de-energized at predetermined intervals for controlling the grip upon the box blank T. The gripper ports are thus controlled to retain the blank in folded condition against the face of the die-head. This pneumatic system includes the conduits 15 and 16 mentioned and a control valve 25 mounted upon the spindle 11 and communicating with the conduit 16 and the power supply hose 17.

This control valve 25 includes a valve disk 26 connected to the supporting spindle 11 and rotatable therewith, a valve disk 27 spaced from the rotary disk, and an intermediate controlling disk 28. The valve disk 27 is centrally transversely apertured to fit snugly upon the supporting spindle and is anchored by means of an anchor rod 29 appropriately supported by the frame 13, thus permitting rotation of the spindle, while the valve disk 27 is restrained against rotation. The intermediate controlling disk 28 also fits snugly upon the spindle 11, but is rotatable thereon and may be turned through a limited angle of rotation by means of a valve controlling mechanism. This mechanism as shown includes a stud 30 secured to the disk 28 and carrying a peripherally grooved roller 31. Spaced parallel operating rods 32 are positioned to seat within the groove of roller 31 at opposite sides thereof and are attached at their inner ends to an arm or projection 33 which may be formed upon a bearing sleeve 34 rotatably mounted upon the spindle 11. This construction provides an operative guideway or frame for operation of the valve. It will thus be seen that the roller 31 will slide idly along the operating rods 32 during longitudinal movements of the supporting spindle 11. However, when the arm 33 is swung the rods 32 will be correspondingly moved and the valve disk 28 will be rotated through a small angle.

Swinging movement of the arm 33 may be effected by means of a cam 35 mounted upon a driving shaft 36 and operatively connected by a rock arm 37 carrying at its outer end a cam roller 38 and connected at its inner end to the arm 33 by a link 39. The cam 35 is constructed and timed to rotate the valve disk 28 at predetermined intervals to admit the vacuum supply or to cut it off from the die-head. A tension spring 40 urges the cam roller 38 into contact with the cam 35.

Each of the valve disks 26, 27 and 28 is provided with smooth even contacting surfaces which are held in close engagement with each other by means of a compression spring 41 compressed between the end disk 27 and an abutment collar 42. Air-tight joints are thus formed between the adjacent contacting disks. Also, the connections between the disks and the spindle 11 are air-tight.

Upon its inner face the valve disk 26 is formed with a circular groove or passageway 43 extend-

ing for a complete circle, and with two radial passageways 44 in communication with the passageway 43 and with the inner conduit 16 through passageways 45 in the wall of the spindle 11. The central or controlling valve disk 28 is provided with a port 46 extending transversely through said disk 28 and positioned for communication at one end with the passageway 43 of the disk 26. The valve disk 27 is also provided at its inner face with an arcuate passageway 47 of approximately the same radius as that of passageway 43 and lying against the adjacent face of the control disk 28. The passageway 47 may be considerably less than 360° in extent, leaving an ungrooved part 48. It will thus be seen that the passageway or port 46 remains in communication with the circular passageway 43 in all rotary positions of the valve disk 26 but that port 46 is only in communication with the passageway 47 when control disk 28 is rocked to the dot and dash position shown in Fig. 4. This rocking is effected by operation of the cam 35 as above described.

When the raised part of the cam 35 contacts with the cam roller 38, the valve disk 28 will be positively rotated to close the valve, and when the raised part of the cam passes by the roller the valve disk 28 will be rotated in the opposite direction to open the valve by means of the spring 49. It will thus be seen that the vacuum supply communicating with the die-head conduits will be controlled through the valve disk 28 under automatic control by the cam 35.

By means of the structure and arrangement set forth, it will therefore be seen that the control valve may be operated to control the pneumatic energy to the die-head in different rotative and longitudinal positions thereof and in different longitudinal and rotative positions of the supporting spindle 11. These functions are of particular importance because by means thereof the gripping and releasing operations of the blank T upon the die-head may be controlled in any position of the latter. The vacuum grip may thus be established at the moment desired in the formative cycles of operation upon the blank and released when it is desired to eject the blank from the die-head after completion of the formative operations. When the blank has been completely formed, as fully described in the prior copending application, the die-head will have been projected forwardly through the breakdown frame 14 into a different formative stage in which the operative parts assume the position as shown in Fig. 2. However, with the improved mechanism described, the pneumatic power is under complete control through the control valve 25 in the various rotative and longitudinal operative positions of the supporting spindle 11.

Port 46 of the control disk 28 is always in communication with the circular passageway 43 of rotary valve disk 26 in any rotative position of the spindle 11. However, the port 46 is closed to power admission by the closure member 48 of the valve disk 27 when disk 28 is in its normal or full line position, as shown in Fig. 4. The pneumatic power is therefore, in this position, cut off from the spindle conduit 16. The disk 27 being anchored against rotation by the anchor rod 29, the port 45, when the disk 28 is rotated to the dot and dash position of Fig. 4, will communicate with the arcuate passageway 47. Power will thus be admitted to the spindle conduit 16 through the passageway 47, port 46, and passageways 43, 44

of the disk 26 and ports 45 through the spindle wall.

Since certain changes may be made in the above construction and different embodiments of the invention could be made without departing from the scope thereof, it is intended that all matter contained in the above description or shown in the accompanying drawings, shall be interpreted as illustrative and not in a limiting sense.

10 Having described our invention, what we claim as new and desire to secure by Letters Patent is:

1. In a fluid power controlling device for box machines, in combination, a longitudinally reciprocable and rotary fluid conduit, a supporting head carried by said conduit for movement with the latter and having a gripper port in fluid communication with the conduit, a control valve mounted upon said conduit for movement therewith and having fluid communication therewith 20 and with a source of fluid power supply, and automatic means for controlling said valve to control fluid power to the conduit and gripper port in different longitudinal positions of said conduit.

2. In a fluid power controlling device for box machines, in combination, a longitudinally reciprocable and rotary fluid conduit, a control valve mounted upon said conduit for reciprocation therewith and having fluid communication therewith and with a source of fluid power supply, and 30 automatic means for opening said valve to admit fluid power to the conduit in one longitudinal and rotative position of the latter and to close said valve in another longitudinal position thereof.

3. In a fluid power controlling device for box machines, in combination, a longitudinally reciprocable and rotary fluid conduit, a control valve mounted upon said conduit for reciprocation therewith and having fluid communication therewith and with a source of fluid power supply, said 35 valve including a valve element rotatable with said conduit, a valve element anchored against rotation with the conduit, an intermediate valve element rotatable with reference to the other two valve elements to open and close the valve, and 40 automatic means for opening said valve to admit fluid power to the conduit in one longitudinal and rotative position of the latter and to close said valve in another longitudinal position of the conduit.

50 4. In a fluid power controlling device for box machines, in combination, a longitudinally reciprocable and rotary fluid conduit, a control valve mounted upon said conduit for reciprocation therewith and having fluid communication therewith and with a source of fluid power supply, said 55 valve including a valve element rotatable with said conduit, a valve element anchored against rotation with the conduit, an intermediate valve element rotatable with reference to the other two valve elements to open and close the valve, and 60 automatic means connected to move said intermediate valve element to control fluid power to the conduit in different longitudinal positions of the latter.

65 5. In a fluid power controlling device for box machines, in combination, a rotary fluid conduit, a control valve mounted upon said conduit and having fluid communication therewith and with a source of fluid power supply, said valve including a valve element attached to and rotatable with said conduit, a valve element anchored against rotation with the conduit, an intermediate valve element rotatable with reference to the other two valve elements, and having its 70 opposite faces in fluid tight contact therewith, an

operating lug mounted upon said intermediate valve element, an elongated operating rod cooperating with said lug, and means for moving said rod transversely of its axis to operate said intermediate valve element to open and close the valve. 5

6. In a fluid power controlling device for box machines, in combination, a longitudinally reciprocable and rotary fluid conduit, a control valve mounted upon said conduit for reciprocation therewith and having fluid communication therewith and with a source of fluid power supply, said valve including a valve element rotatable with said conduit, a valve element anchored against rotation with the conduit, an intermediate valve element rotatable with reference to the other two valve elements, and having its opposite faces in fluid tight contact therewith, and an operating connection with said intermediate valve element including a lug and an elongated guideway for rotating said intermediate 20 element in different longitudinal positions of said conduit.

7. A valve having a plurality of cooperating disks positioned side by side, one disk being rotatably mounted and having an endless arcuate 25 passageway with an exit port in communication therewith and extending inwardly from said passageway for communication with an inwardly disposed conduit, another disk being relatively stationary and having a discontinuous arcuate 30 passageway with an ingress port in communication therewith and having a closure member at one end of the passageway, and an intermediate movable controlling disk having a port positioned in communication with both of said passageways 35 in one position thereof and in closing relation with said closure member in another position.

8. In a box making machine, in combination, a blank shaping head, a rotatable and longitudinally movable head supporting spindle having a conduit in communication with said head, and a combined power controlling valve and power supply coupling mounted upon said spindle for longitudinal movement therewith, said valve having a part mounted upon said spindle for 40 rotation therewith and an adjacent companion part mounted upon said spindle for rotation relatively thereto for controlling power supply to the shaping head. 45

9. In a box machine, in combination, a shaping 50 head having a peripheral surface for receiving a blank thereagainst, and having a plurality of pneumatic conduits communicating with said surface, a rotary and longitudinally movable supporting spindle for said shaping head having a 55 pneumatic conduit therein communicating with said first mentioned conduits, a pneumatic valve mounted on said spindle and having a valve part rotatable with said spindle, a valve part anchored against rotation, and a movable valve 60 control part, and mechanism for controlling said valve control part at predetermined intervals.

10. In a box machine, in combination, a shaping head having a peripheral surface for receiving a blank thereagainst, and having a plurality 65 of pneumatic conduits communicating with said surface, a rotary and longitudinally movable supporting spindle for said shaping head having a pneumatic conduit therein communicating with said first mentioned conduits, a pneumatic valve 70 mounted on said spindle and having a valve part rotatable with said spindle, and an independently rotatable companion part, and operating connections for operating said companion part in different longitudinal positions of said spindle. 75

11. In a fluid power controlling device, in combination, a die head, a supporting spindle for said die head mounted for longitudinal reciprocation and having a conduit in communication with said head, a power controlling valve mounted upon said spindle for reciprocation therewith and having connections for controlling fluid power to said conduit, and an operating device for said valve including an elongated guideway connected to the valve for operation thereof in different longitudinal positions of said reciprocating spindle.

12. A valve having a plurality of co-operating disks positioned side by side and in contact with each other, one of said disks being rotatively mounted and having a curvilinear passageway extending continuously in an endless path and having an exit port in communication with the passageway, another of said disks being anchored against rotation with the said rotary disk and having a curvilinear passageway with an ingress port in communication therewith and having a closure member positioned at one end of the passageway, and a third of said disks being rotatably mounted with reference to the other two disks and positioned therebetween and having a port opening at opposite faces thereof in position for communication with both of said passageways in one position thereof and in closing relation with said closure member in another position thereof.

13. In a device of the character described, in combination, a valve having a plurality of co-operating disks positioned side by side and in contact with each other, one of said disks being rotatively mounted and having a curvilinear passageway extending continuously in an endless path and having an exit port in communication with the passageway, another of said disks being anchored against rotation with the said rotary disk and having a discontinuous curvilinear passageway with an ingress port in communication therewith and having a closure member positioned at one end of the passageway, and a third of said disks being rotatably mounted with reference to the other two disks and positioned there-

between and having a port opening at opposite faces thereof in position for communication with both of said passageways in one position thereof and in closing relation with said closure member in another position thereof, and an automatic operating device connected to move said third disk into opening and closing position at predetermined intervals.

14. In a fluid power controlling device for box machines, in combination, a rotary and longitudinally reciprocable spindle having an elongated conduit extending therealong, a supporting head carried by said spindle for movements therewith and having a gripper port in fluid communication with the conduit, a controlling valve mounted upon said spindle for movements therewith and having fluid communication with said conduit and with a source of fluid power supply, and an automatic valve operating device connected to said valve to open and close the same so as to effect control of fluid power to the conduit and to said gripper port in different rotative positions of said spindle.

15. In a fluid power controlling device for box machines, in combination, a rotary and longitudinally reciprocable spindle having an elongated conduit extending therealong, a supporting head carried by said spindle for movements therewith and having a gripper port in fluid communication with the conduit, a control valve mounted upon said spindle for movements therewith and having fluid communication with said conduit and with a source of fluid power supply, said valve including a valve element rotatable with said spindle, a valve element anchored against rotation with the spindle, an intermediate valve element rotatable with reference to the other two valve elements, and an automatic valve operating device connected for rotating said intermediate element to admit fluid power to the conduit and gripper port in one rotative position of said spindle and to cut off the power in another rotative position of the spindle.
